(57) **CLAIM**

The ornamental design for a spray bottle with storage compartments, as shown and described.

DESCRIPTION

FIG. 1 is a perspective view of a spray bottle with storage compartments, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof, in which the storage compartments are shown separated.

The broken lines depict portions of the spray bottle with storage compartments that form no part of the claimed design.

1 Claim, 7 Drawing Sheets
